INVENTOR

UNITED STATES PATENT OFFICE.

FRED B. NORTON, OF CARTHAGE, MISSOURI.

MEASURING-FUNNEL.

1,359,730.

Specification of Letters Patent. Patented Nov. 23, 1920.

Application filed February 2, 1920. Serial No. 355,849.

To all whom it may concern:

Be it known that I, FRED B. NORTON, a citizen of the United States of America, residing at Carthage, in the county of Jasper and State of Missouri, have invented certain new and useful Improvements in Measuring-Funnels, of which the following is a specification.

My invention relates to improvements in receptacles for measuring and dispensing liquids.

The principal object of my invention is to provide means for accurately measuring liquids, and transferring the same from one receptacle to another without loss of contents.

In the accompanying drawing herein, I have illustrated a preferred embodiment of my invention:

Figure 1 is a vertical sectional view of my invention;

Fig. 2 is a detail view partly in section of the valve in closed position; and

Fig. 3 is a view similar to Fig. 2 showing the valve in open position.

Referring more particularly to the drawings wherein like reference numerals refer to corresponding parts 1 designates a can or receptacle, preferably of light sheet metal and cylindrical in shape. The receptacle 1 is provided with handle 7, pouring lip 18 and supporting legs 16, the latter being attached in any suitable manner (not shown) to the bottom 19.

Depending from the bottom 19 of the receptacle 1 is a cylindrical spout 13 apertured as at 12 to provide air outlets. Located within the spout 13 is a tubular valve housing 11 communicating at its upper end with a centrally disposed opening 20 in the bottom 19 and terminating at its lower end midway of the length of the spout 13. Slidably positioned within this sleeve 11 is a tubular sleeve valve 15 formed with a head 9 adapted to seat, when the valve is in closed position, upon the upper end of the housing 11, a cork or other washer 10 beneath the head 9 insuring a liquid tight joint.

The valve 15 is adapted to be reciprocated within the sleeve 11 by means of a hand lever 2 pivoted adjacent one end as at 5 to an ear 6 on the receptacle 1 and connected at its other end, to a link or rod 4 in turn connected to an eye 8 secured to the valve 15.

The operation of my device is as follows: Assuming the receptacle 1 to be full or partially full of liquid the user can readily transfer the contents of same to another vessel by opening the valve 15. As previously explained this is accomplished by pressing down upon the thumb piece 21 of the lever 2, whereupon the valve will be elevated against the tension of coil spring 14 until the openings 17 extend above the bottom 19. The liquid will then flow through the openings 17, down through the sleeve valve and out through the spout 13, this flow being accelerated by the entrance of air through the openings 12. When pressure on the lever 2 is released, the spring 14 will automatically act to seat the housing 11 and shut off the flow of liquid. It will be noted from an inspection of the drawing that the spring 14 is secured at its lower end to the valve 15 and at its upper end bears against the housing 11.

Having thus described my invention, what I claim is:

A device of the class described, comprising a receptacle having an opening in the bottom wall thereof, a tubular housing depending from said opening, an apertured spout inclosing said housing, a tubular sleeve valve slidable in said housing and formed with a head adapted to seat upon the upper end of said housing, a coil spring secured at one end to said valve and at its other end bearing against said housing for normally holding said valve to its seat, said valve having liquid inlet openings in its sides normally covered by said housing and means for raising said valve from its seat.

In testimony whereof I affix my signature.

FRED B. NORTON.
